F.I. Bailey Sheet 2.2 Sheets

Card Printing Press.

No 17549. Patented June 16, 1857.

UNITED STATES PATENT OFFICE.

FRANKLIN L. BAILEY, OF BOSTON, MASSACHUSETTS.

CARD-PRINTING PRESS.

Specification of Letters Patent No. 17,549, dated June 16, 1857.

To all whom it may concern:

Be it known that I, FRANKLIN L. BAILEY, of Boston, in the county of Suffolk and State of Massachusetts, have invented an Improved Card-Printing Press; and I do hereby declare that the same is fully described and represented in the following specification and the accompanying drawings, of which—

10 Figure 1, denotes a top view of such press. Fig. 2, a side elevation of it. Fig. 3, a central, vertical and longitudinal section of it. Fig. 4, an inner side view of the paper bed and its guides. Fig. 5, is a horizontal section of the paper bed and guides, the same being made to represent the cutting knife to be hereinafter described.

15 In these drawings, A, exhibits the frame of the machine, the same being constructed so as to carry and permit to slide forward and backward within it, the movable platen, B. The type or form of type is shown at C, in Fig. 3, as affixed to the inner face of the platen, such platen being driven forward by the action of the cam, a, against a

20 friction roller, b, the same being arranged as shown in Figs. 1 and 3. In other words, the cam is fixed on a rotary shaft, D, and works against the roller, and while being revolved by such shaft, springs, E, E, serve to draw the platen backward during recession of the cam on the roller.

25 A plate or second frame, F, is hinged at its foot to the frame, A, so that it may vibrate or play toward and away from the platen; this frame carries the card or paper bed, G, against which the card is pressed while being printed. On a shaft, H, (arranged at the lower part of the frame, A,)

30 two adjustable guides I, I, are fixed, the said guides extending upward between the platen and the bed, G. Besides these guides there is a stop or rest, K, that projects upward from the middle of the shaft H, and

35 should be so applied to such shaft as to enable it to be raised and lowered and fixed in position as occasion may require.

By means of a spring, L, extending from the shaft, H, to the frame, F, the shaft 50 may be turned so as to spring the guides I, I, and the rest K, away from the bed. Applied to the upper part of the rest is a bent spring, M, which may be termed the “spring card holder,” the same being used 55 in connection with the feeding guides or mechanism, and the platen and bed as

will be hereinafter described. A sliding cutting block N, carrying a knife, o, is applied to the lower part of the inner side of the frame F, and by means of an adjusting screw, d, and the slot, e. By such means, the said knife and block may be raised or lowered as occasion may require. Two shafts, P, and R, are arranged in a rocker frame, W, fixed in the upper part of the frame, F; one of them, viz., P, carries a feed roller, S, in its middle. The other has a roller or disk, T, affixed to it, and it also carries another sliding roller, U, which rests against a spring, V, placed on the shaft as shown in Fig. 1. A ratchet, f, is fixed on the shaft, P. Operating in connection with the same is a pinion, g, which rotates freely on the shaft P, and carries a spring impelling pawl, h, the same being as shown in Fig. 6, which is an inner side view of the ratchet, the gear, and spring pawl. The gear, g, engages with a sectoral vibrating rack, i, which is so connected with the platen by a pitman, k, as to be moved with 80 and by it.

When the press is in operation or prepared for printing cards, the frame, F, should be locked firmly to the frame, A, by means of pins, l, l, extending through ears m, m, of the frame, A, and into said frame F. The apparatus arranged at the upper part of the frame F, is for the purpose of feeding card board in one continuous strip into the press, each card after being printed and moved below the knife being separated from the strip by the action of the knife, which is pressed forward toward the cutting bed while the platen is being driven up to produce an impression. The 90 guides, I, I, at the same time are pressed forward by the platen so as to force the knife up to its block. The guides also perform another function, that is, they enable a person to print common cards or separate 95 pieces of card board. In order to accomplish this, a card is dropped down between the guides (which are formed so as to enable it to pass downward) until it rests on the stop, K, and in front of the card holder, M. 100

When the platen is forced forward, it presses the guides, I, I, and stop, K, forward with it and causes the card holder, M, to be pressed against the card so as to force the card close up against the paper 110 bed, G, before the type may come into contact with the said card. By thus holding

the card firmly against the bed before it is met or touched by the printing face of the type, the imprint on the card is performed to much better advantage, and without being blurred or otherwise defaced.

The guides, I, I, are inclined back from the vertical plane, as shown in the drawings. This feature causes the card in descending to rest against and to be supported by them, 10 and enables me to employ guides without any front lips to them which, when used, more or less prevent the card from being forced up to the bed.

The card holder is used in connection with 15 the feeding apparatus, whether such be for feeding cards by hand or in a continuous strip, the machine being adapted for either purpose.

When the platen is driven backward the 20 feed roller S, will be put in movement so as to feed the strip of card board downward one edge of the said strip being made to rest against the roller T, and be pressed against the inner side of the roller T, and 25 by the action of the sliding roller, U, against the opposite edge of said strip.

In Figs. 1, and 3, the position of the strip of card board is represented by red lines, it being made to enter the machine through a 30 groove, o, in a plate, p, affixed to the top of the frame, F. By applying the guides I, I, to the card so that they may spring away from it, they not only enable the cutting knife to be moved backward, the same being forced by a spring (shown in Figs. 3, and 4,) but they prevent the card which is 35 being dropped into the machine or down toward the stop, K, from contact with and friction against the surface of the bed, 40 whereby its descent may be retarded or arrested.

Fig. 7, is a sectional view of the rocker frame W, and the upper part of the frame, F. In this figure, it will be seen that the 45 frame, W, is supported at its middle on a rock shaft, ledge or fulcrum, t, and that adjusting screws, u, u, extend down through the frame, W, and are screwed into the upper part of the frame F. The object of applying the feed and pressure rollers in such 50 manner, to the frame, F is to enable the feeding rollers to be tipped a little as occasion may require, in order to cause the sheet of card board to move downward in a

proper manner with respect to the form of 55 type, after the latter has been adjusted on the platen, it being understood that the shaft, R, freely rotates when the paper is pressed against it by the roller, S, and such roller is in revolution.

60

I do not claim the combination of feeding guides with the bed, against which the card is to be pressed, but

I claim—

1. Applying the guides, I, I, to the bed 65 substantially as described, that is, so that they may spring or move away from and toward it, and thus not only relieve the card from contact with and friction against the surface of the bed, while such card is descending in the guides, but also to operate the knife and allow it to move backward substantially as specified.

2. I also claim arranging the guides I, I, so as to incline back from the vertical plane, 75 the same being for the purpose of supporting the card and enabling the guides to be used without any front lips as described.

3. I also claim the combination of the 80 spring card holder M, with the card rest or stop, K, and the feeding guides or mechanism and the bed and platen the said card holder being applied to the stop, K, so as to operate substantially in manner and for the purposes set forth.

4. I also claim applying the feed and 85 pressure rollers in a rocker frame combined with the vibrating frame, F, and provided with adjustments arranged so as to enable the rocker frame to be tipped a little as occasion may require to cause the continuous sheet of paper or card board to operate properly with respect to the position of the form on the platen.

5. I also claim arranging on the shaft R, 95 and so as to operate with a stationary roller as described and with the feeding roller, a spring pressure roller to act against the edge of the sheet of card so as to maintain its opposite edge in a proper position with respect to the type.

In testimony whereof, I have hereunto set my signature this 8th day of January A. D. 1857.

FRANKLIN L. BAILEY.
